UNITED STATES PATENT OFFICE.

AUGUST WIEBKE AND ROBERT E. GRUWELL, OF MILES CITY, MONTANA.

CURRENT-MOTOR.

No. 810,814.

Specification of Letters Patent.

Patented Jan. 16, 1906.

Application filed January 28, 1905. Serial No. 243,026.

To all whom it may concern:

Be it known that we, AUGUST WIEBKE and ROBERT E. GRUWELL, citizens of the United States, residing at Miles City, in the county 5 of Custer and State of Montana, have invented certain new and useful Improvements in Current-Motors; and we do hereby declare the following to be a full, clear, and exact description of the invention, such as will enable 10 others skilled in the art to which it appertains to make and use the same.

Our invention relates to current-motors of the general character disclosed in the application of August Wiebke, Serial No. 216,463, 15 filed July 14, 1904, and has for its object generally to improve current-motors of this type.

To the above ends the invention consists of the novel devices and combinations of devices hereinafter described, and defined in the 20 claims.

The invention is illustrated in the accompanying drawings, wherein like characters indicate like parts throughout both views.

Figure 1 is a plan view of the improved 25 motor, and Fig. 2 is a vertical section taken on the line $x^2 x^2$ of Fig. 1.

The numeral 1 indicates boat-like floats which are rigidly tied together by timbers 2 to form a raft which carries the motor, pump, 30 and connections between the same. As shown, three floats 1 are employed, and these are spaced apart to afford spaces in which work a pair of water-wheels 3, the shafts 4 of which are loosely journaled in bearings 5 on 35 said floats, extend in axial alinement therewith, but are separated at their abutting ends.

The numeral 6 indicates a spur-gear which is mounted loosely on the adjacent ends of 40 the two shafts 4 and the hub of which is provided at each end with a half-clutch 7. Sliding half-clutches 8 are carried, one by each shaft 4, are keyed to revolve with the respective shafts, and coöperate one with each of 45 the half-clutches 7. Levers 9 suitably mounted on the central float, control the movements and positions of the two sliding half-clutches. The gear 6, while loose for rotation with respect to the shafts 4, is by suitable means (not shown) held against lateral 50 movements thereon. Said gear 6 meshes with a spur-gear 10, carried by a crank-shaft 11, mounted in bearings 12 on the central float 1 and provided at its ends with 55 cranks 13, that extends in diametrically opposite directions.

The sliding half-clutches 8 are so set on the shafts 4 and are so related to the half-clutches 7 that when both are engaged with their respective half-clutches 7 the blades of the one 60 water-wheel will stand circumferentially half-way between the blades of the other water-wheel, thereby giving a continuous application of power. Each water-wheel has one blade which is pivotally mounted for movement into an inoperative position, and this is best accomplished by pivotally connecting the arms 3^a of said movable blade at 14 to radial stub-arms 15 of the coöperating shaft 4. To lock the said arms 3^a in radial or operative positions, as shown in the drawings, lock-bolts 16 are mounted for sliding movements in suitable bearings on the stub-arms 15 and are provided with lock-fingers 17, that are adapted to enter perforations in the inner 65 ends of said arms—*i. e.*, light springs 18 react against the stub-arms 15 and against shoulders on the lock-bolts to normally hold the lock-fingers 17 in engagement with the said arms 3^a. As is evident, by taking hold of 70 the finger-piece 19 at the outer end of the rod 16 and drawing upward thereon the pivotally-movable blade of the wheel may be released at will, thereby rendering the wheel 75 inoperative. It may be here remarked that 80 the water-wheels will run at such speed that the said finger-piece 19 may be easily engaged by a person standing in the vicinity thereof.

The pumps, of which there is one for each water-wheel, are of the cylinder-and-piston 85 type and are set upright, with their long cylinders 20 rigidly secured to the central float 1 and with their lower ends opening through the bottom of said float. Near their upper ends the cylinders 20 are provided with discharge-spouts 21. The piston-rods 22 at their upper ends are connected to the forward ends of long levers 23, which levers are pivoted at their intermediate portions to the upper ends of long uprights 24, that are also 90 rigidly secured to the central float 1. The rear ends of the levers 23 are connected one to each of the cranks 13 of the shaft 11 by long connecting-rods 25. The said two pumps are therefore thrown into action in 95 alternate order—that is, the piston of the one pump is given its operative upward stroke while the piston of the other pump is being given its inoperative downward stroke, and vice versa.

When the pivoted blade of the water-wheel is tripped and rendered inoperative, it is de- 100 105 110

sirable to positively stop the wheel in a position in which no one of its fixed blades will project into the water. To accomplish this, we provide for each water-wheel a stop, preferably in the form of a sliding bar 26, mounted in suitable bearings 27 on the timbers 2 and provided with a pronged head 28, adapted to engage the edge of one of the fixed blades of the wheel. The slides 26 are preferably moved by levers 29, pivoted at 30 to one of the beams 2.

The device described, while extremely simple, is efficient for the purposes had in view, and under the force of a running stream 15 will elevate water to very great heights. The floating support should of course be anchored in the stream. It may be assumed that the current flows and that the wheels turn in the directions indicated by the arrows 20 marked on Fig. 1. To stop the wheel when its movable blade has been tripped or released, the stop-head 28 should be projected into the path of movement of the released blade while the latter is moving downward. 25 This being done, the said blade will be caused to move backward against the blade which follows it and will then stop the wheel in a position in which no one of the blades of the wheel will project into the water.

30 By means of the clutch devices described either one or both of the wheels may be coupled to the crank-shaft 11, and thus a variable-power device is afforded. The water discharged from the spouts of the two pumps 35 may be carried off either by independent or by a common trough or spout. (Not shown.)

From what has been said it will be understood that the device described is capable of modification within the scope of our invention as herein set forth and claimed.

What we claim, and desire to secure by Letters Patent of the United States, is as follows:

1. The combination with a support, of a 45 water-wheel mounted thereon with its axis

above the water-line, said water-wheel having a blade movable pivotally into an inoperative position, and a lock for securing said blade in operative position and for releasing the same, substantially as described. 50

2. The combination with a support, of a water-wheel mounted thereon, with its axis above the water, said wheel having a pivoted blade movable into an inoperative position, and a stop mounted on said support and 55 movable into the path of the blades of the wheel, substantially as described.

3. The combination with a floating support, of a water-wheel mounted on said support, with its axis above the water, said 60 wheel having a blade movable pivotally into an inoperative position, a lock for securing said blade in an operative position, and for releasing the same, and a stop mounted on said support and movable into the path of the 65 blades of said wheel, to positively stop said wheel when its pivoted blade is released, substantially as described.

4. The combination with a floating support, of a pair of water-wheels mounted 70 thereon, with their shafts in axial alinement, a gear loosely mounted on the adjacent ends of the two shafts, a pair of clutches for connecting said wheels to said gear, arranged to couple said wheels with the blades of the one 75 set ahead of the blades of the other, a gear meshing with the aforesaid gear, a pair of oppositely-projecting cranks connected to said latter gear, a pair of pumps mounted on said support, and connections between said 80 two pumps and said two cranks, substantially as described.

In testimony whereof we affix our signatures in presence of two witnesses.

AUGUST WIEBKE.
ROBERT E. GRUWELL.
